METHOD OF TREATING SOUR HYDRO-CARBON OIL

Walter V. Overbaugh, Fishkill, N. Y., assignor to
The Texas Company, New York, N. Y., a corpora-
tion of Delaware

Application December 27, 1932, Serial No. 648,856

3 Claims. (Cl. 196—33)

This invention relates to a method of treating petroleum hydrocarbon oils and more particularly to a process of sweetening light hydrocarbon distillates prepared by the distillation or 5 cracking of petroleum.

More specifically, my invention relates to a method of sweetening naphthas containing undesirable odorous sulfur compounds wherein the untreated naphtha is mixed with a varying portion 10 of sweetened naphtha to form a solution and then subjecting this solution to the action of a sweetening reagent which may either be an alkaline solution of sodium plumbite, a suspension of lead sulfide in an alkaline solution or any 15 other reagent capable of transforming mercaptans into disulfides.

Untreated naphthas contain, among other sulfur compounds, a certain group known as mercaptans. These compounds impart to the naphthas in which they are present extremely unpleasant odors as well as rendering the naphthas corrosive to certain metals. In refinery terminology such naphthas are spoken of as being sour.

Various methods have been developed for sweetening sour naphthas. The most important of these methods comprises reacting the sour naphthas with alkaline solutions of sodium plumbite whereby the mercaptans are converted 20 to the corresponding oil-soluble lead mercaptides. The last named compounds are then in turn converted to the disulfides by treating the naphtha solution of the lead mercaptides with a proper amount of elementary sulfur. The following 25 equations illustrate generally the above described reactions:

The sweetening of sour hydrocarbons may also 45 be brought about by treating them with suspensions of lead sulfide in alkaline solutions. Foremost among the treating suspensions is one of lead sulfide in sodium hydroxide. In some cases 50 it is found possible to effect an efficient conversion of mercaptans to the corresponding disulfides by simply agitating the sour hydrocarbon oil with the treating suspension. In some operations, it may be desirable to introduce oxygen 55

into the reaction in order to facilitate the conversion of the mercaptans.

I have found that if the sour naphtha is diluted with varying amounts of naphtha which has already been sweetened and the resulting solution 5 is subjected to treatment, with either an alkaline sodium plumbite solution or a suspension of lead sulfide in an alkaline solution, that the sour hydrocarbons may be sweetened much more rapidly and much more efficiently. For example, when 10 treating a sour naphtha which requires one barrel of a standard sodium plumbite solution for each 250 barrels of naphtha, I have found that five times as much naphtha may be sweetened 15 by recirculating from one-half to ten volumes of 15 sweetened naphtha to each volume of sour naphtha.

I have found that the greatly increased efficiency may also be obtained by treating the naphtha in accordance with my invention with 20 an alkaline suspension of lead sulfide. In this case, the reagent may be used for sweetening unlimited quantities of sour naphtha, the only limitation imposed appearing to be the loss of lead sulfide and caustic solution due to the carrying- 25 over effect. By replenishing the quantities of lead sulfide and alkaline solution from time to time, it is possible to carry on the process continuously over an extended period of time.

My invention may be used in any of the conventional treating systems for sweetening sour hydrocarbon oils. Not only does the invention find application in the usual parallel flow treating systems but also in those systems where the sour naphtha and treating reagent are flowed 35 countercurrently.

Suitable forms of apparatus for carrying on my invention are shown in the accompanying drawings in which:

Fig. 1 discloses an apparatus suitable for treating naphtha with a parallel flow of sweetening reagent.

Fig. 2 discloses an apparatus in which naphtha may be treated with a countercurrently flowing stream of sweetening reagent.

Fig. 1 is a diagrammatic view showing an apparatus which may be used for the concurrent sweetening of a sour naphtha with a suitable reagent. Fig. 2 is a diagrammatical view of an apparatus suitable for countercurrent treatment 50 of sour naphtha with a sweetening reagent.

In Fig. 1, the numeral 10 designates a storage tank for sour naphtha. This tank is fitted with a drawoff line 11 controlled by the valve 12 which enters the intake side of the charge pump 13. 55

This pump discharges through the line 14 through the valves 19 and 20 into the mixing device 21. There is fitted around the valve 19 the by-pass line 16 controlled by the valves 15 and 18 which line has interposed in it the sulfur pot 17.

The numerals 22 and 23 designate storage tanks for doctor solution and suspension of lead sulfide in caustic soda solution respectively. Each 10 of these tanks is equipped with a drawoff line indicated respectively by the numerals 24 and 25 controlled by the valves 26 and 27. These drawoff lines are connected to a common line 28 which leads to the intake side of the pump 29. 15 This pump discharges through the line 30 controlled by the valve 31 into the four-way fitting 32 through the line 33 controlled by the valve 34 into the four-way fitting 35 and thence through the line 36 controlled by the valve 37 which connects with the intake side of the circulating pump 38. 20 This pump discharges through the line 39 controlled by the valve 40 into the line 14 at a point intermediate the valve 20 and the input side of the mixing chamber 21.

25 The mixing device 21 discharges through the line 41 controlled by the valve 42 into the settling chamber 43. This settling chamber, which may with advantage be provided with a conical bottom, is equipped at its lowermost point with a draw-off line 44 controlled by the valve 45 which enters the four-way fitting or cross 35, while it is fitted at its uppermost point with a liquid drawoff line 46 controlled by the valves 47 and 48 and which enters the settling chamber 49 at an intermediate 35 point.

The settling chamber 49 may advantageously be of the same construction as the settling chamber 43. It is fitted at its bottom with a drawoff line 50 controlled by the valves 51 and 52 which 40 line is connected to the cross fitting 35. The cross fitting 32 is connected in turn with the spent treating reagent tank 55 by means of the line 53 controlled by the valve 54. The line 50 is fitted at a point intermediate the valves 51 and 52 with a line 57 controlled by the valve 58 which connects the line 50 with the cross fitting 35.

The top of the settling chamber 49 is equipped with a drawoff line 59 controlled by the valves 60 and 61 which line connects the settling chamber to the storage tank 62 for treated naphtha. There is manifolded to the line 59 intermediate the valves 60 and 61 the line 63 controlled by the valve 64 which enters the line 36 at a point intermediate the valve 37 and the intake side of 55 the pump 38. At a point between the valves 47 and 48, the line 46 is joined to the line 63 by means of the line 65 controlled by the valve 66.

In a typical operation of the process employed by my invention in connection with the apparatus shown in Fig. 1, sour naphtha is drawn from the storage tank 10 and delivered to the intake side of the pump 13. This pump delivers the naphtha under a suitable pressure through the line 14 into the mixing device 21. In order to permit of the 60 solution by the untreated naphtha of a sufficient quantity of sulfur, a controlled flow of the naphtha is by-passed through the sulfur pot 17.

A charge of treating solution is introduced into the system from either one of the tanks 22 or 70 23 by means of the pump 29 through the lines 30, 33 and 36 and the pump 38. The principal portion of this treating solution accumulates in the settling chamber 43, the lower portion of which serves as a storage therefor.

75 In beginning the operation of the process, sour

naphtha and a proportioned amount of treating solution are mixed in the mixing device 21. The mixture formed therein is discharged through the line 41 and the valve 42 into the settling chamber 43 wherein the treated naphtha separates quite extensively from the treating reagent. The latter settles to the bottom in a pool while the treated naphtha is drawn off from the top through the line 46 and discharged into the settling chamber 49. Here the remaining traces 5 of treating reagent settle out and the clear treated naphtha is drawn off from the top through the line 59 and delivered to the storage tank 62. When this condition has been established, that is to say, when treated naphtha is discharged from the top of the settling chamber 59, a quantity of the treated naphtha is by-passed through the line 63 and delivered to the intake side of the circulating pump 38. This circulating pump discharges the treated naphtha into the line 14 through 20 which a flow of sour naphtha is maintained. Simultaneously, a proportioned amount of treating reagent is drawn off from the bottom of the settling chambers 43 and 49 and together delivered to the mixing device 21 a mixture of treated naphtha, sour naphtha and treating reagent and this mixture after vigorous agitation is introduced into the settling chamber 43. The 25 rates of flow of the various streams are so regulated by the control of the various valves that the 30 overflow from the settler 49 is at all times maintained sweet while using the minimum amount of treating reagents.

In Fig. 2, the numeral 10 designates a storage 35 for sour naphtha. This tank is equipped with a drawoff line 11 controlled by the valve 12 which connects the tank 10 with the intake side of the pump 13. This pump discharges through the line 14 controlled by the valves 19 and 20 into a mixing device 21. There is fitted about the valve 19 a by-pass line 16 in which there is interposed a sulfur pot 17. This by-pass line is controlled by the valves 15 and 18. The mixing device 21 discharges through the line 70 controlled by the valve 71 into the settling chamber 72.

The settling chamber 72 is fitted at its uppermost point with a drawoff line 73 controlled by the valve 74 which connects the settling chamber with the mixing device 75. This mixing device is provided with a line 76 controlled by the valve 77 which enters the discharge side of the pump 78. The intake side of this pump is connected with a tank 81 for treating reagent through the line 79 controlled by the valve 80. This tank is connected by means of the line 82 controlled by the valve 83 with the bottom of the settling chamber 72. The line 82 is connected with the line 79 by means of the branch line 99 controlled by the valve 100. Into this branch line at a point intermediate the line 82 and the valve 100 there 55 is fitted the drawoff line 102 controlled by the valve 103 which leads to a storage (not shown) for spent treating reagent. By the proper manipulation of the necessary valves, it is possible to either circulate treating reagent or to draw 60 off treating reagent which has become spent.

The mixing chamber 75 discharges through the line 84 controlled by the valve 85 into the settling chamber 86. The bottom of this settling chamber is provided with a drawoff line 87 controlled by the valve 88 which connects through the pump 89 and the valve 90 with the mixing device 21. The top of the settling chamber 86 is equipped with a drawoff line 91 controlled by the valves 92 and 93 which leads to the treated naphtha stor- 75

age tank 98. There is manifolded to the line 91 at a point intermediate the valves 92 and 93 the line 94 controlled by the valve 95 which leads through the circulating pump 96 and the valve 5 97 into the line 14 at a point intermediate the valves 19 and 20.

In a typical operation of the process in connection with the apparatus shown in Fig. 2, a sour naphtha, that is, a naphtha containing undesirable mercaptan bodies, is drawn from a storage tank 10 by the pump 13 and delivered by this pump under a suitable pressure into the line 14 which leads to the mixing device 21. A portion of the sour naphtha may be by-passed through 10 the sulfur pot 17 where enough sulfur is dissolved by the naphtha to permit of the subsequent decomposition of the lead mercaptides.

There is also introduced into the mixing device 21 a quantity of naphtha which has already been 20 sweetened and which is recycled from a subsequent step in the process. The mixture of sweetened and unsweetened naphtha is thoroughly agitated with treating reagent delivered from the bottom of the settling chamber 86. In this manner the 25 sour naphtha is partly sweetened and the mixture of treated naphtha, partly treated naphtha and treating reagent is delivered into the settling chamber 72 wherein the separation of the treating reagent from the naphtha is brought about. 30 The treating reagent which settles to the bottom of the settling chamber is permitted to flow through the line 82 controlled by the valve 83 into the treating reagent storage tank 81. The supernatant layer of partly treated naphtha 35 which separates out in the settling chamber 72 is drawn off from the top of the chamber through the line 73 controlled by the valve 74 and delivered into the mixing device 75 wherein it is agitated with treating reagent delivered from 40 the storage tank 81 by means of the pump 78. By this treatment, the last traces of mercaptans are removed and the naphtha is completely sweetened. The mixture of treated naphtha and treating reagent is delivered to the settling chamber 45 86 through the line 84 controlled by the valve 85. In this settling chamber, a complete separation of the treated naphtha from the treating reagent takes place. The treated naphtha is drawn off from the top of this chamber and delivered to the storage tank 98 through the line 50 91 controlled by the valves 92 and 93. Facilities are provided in the form of a line 94 controlled by the valve 95 whereby a portion of the treated naphtha may be recycled to the mixing device 55 21.

The treating reagent which settles out as a pool in the bottom of the settling chamber 86 is drawn off in a controlled stream through the line 87 controlled by the valve 88 and is circulated to the 60 mixing device 21 by means of the pump 89.

In carrying out the herein disclosed invention, it may be advantageous to commence treating with the usual alkaline solution of sodium plumbite. After this treating reagent has been in use 65 for a certain length of time, it may be found that the caustic soluble lead has been reduced to a value approaching zero. Ordinarily, it is found necessary to draw off the reagent when it has become spent to such an extent and to replace 70 it with a fresh alkaline solution of sodium plumbite. I have found it desirable in some cases to continue using the spent doctor solution which consists of caustic soda solution and lead sulfide and, if necessary, to subject it to a heat treatment

or reaction with oxygen whereby the quantities of caustic soluble lead may be increased to a value approaching the original concentration.

In the treatment of certain naphthas which contain low molecular weight mercaptans, that is to say, mercaptans which are highly reactive, it is unnecessary to reactivate the spent doctor solution in which case the reaction may be carried out while using simply a suspension of lead sulfide in a water solution of sodium hydroxide 10 or other alkaline solution.

Various ratios of sweetened to sour naphthas may be maintained in carrying out the treating reaction. It is obvious that if the quantity of treated naphtha which is recirculated is exceedingly large, a diminution in the output of a treating battery will result. This is directly due to the fact that there is a critical flow rate which may not be exceeded in any of the flow chambers if a suitable separation of the naphtha from the 15 treating reagent is to be effected. If the rate of flow through the settlers is maintained near the critical flow rate, an undesirable and uneconomical carrying over of treating reagent by the sweetened naphtha results. I have found that in most 20 treating operations a ratio of sweetened naphtha to one part sour naphtha of from one-half to ten is the most effective range. However, greater or smaller ratios than these may be found necessary 25 in the treatment of various naphthas.

Obviously many modifications and variations of the invention, as hereinbefore set forth, may be made without departing from the spirit and scope thereof, and therefore only such limitations 30 should be imposed as are indicated in the appended claims.

I claim:

1. A method of treating sour hydrocarbon oil which comprises mixing the sour hydrocarbon oil with from one-half to ten times its volume of sweetened oil to form a mixture and then agitating the mixture, in the presence of sulfur, with a treating reagent selected from a group consisting of an alkaline solution of sodium plumbite and a suspension of lead sulfide in an alkaline solution, 40 subjecting the reaction mixture to settling, drawing off the sweetened oil and returning the treating reagent to further reaction.

2. A method of treating sour hydrocarbon oil which comprises mixing the sour hydrocarbon oil with from one-half to ten times its volume of sweetened oil to form a mixture and then subjecting the mixture to sweetening treatment in the presence of sulfur and an alkaline solution of sodium plumbite as a treating reagent until the caustic soluble lead content of the treating reagent has been converted into lead sulfide and then continuing to treat a mixture consisting of sour hydrocarbon oil and from one-half to ten 50 times its volume of sweetened oil with the lead sulfide suspension thus formed and sulfur.

3. In the method of sweetening sour hydrocarbon oil wherein a sour hydrocarbon oil is treated, in the presence of sulfur, with a sweetening reagent selected from the group consisting of an alkaline solution of sodium plumbite and a suspension of lead sulfide in an alkaline solution in a 55 treating zone, the step consisting in recirculating sweetened oil to the treating zone in sufficient quantity that the ratio of sour naphtha to sweetened naphtha is within the limits of 1:1/2 and 1:10, whereby the rapidity and efficiency of the sweetening process is improved.

WALTER V. OVERBAUGH.
